PAD HOLDER

David Jenkins, Seattle, Wash.

Application May 15, 1946, Serial No. 669,929

5 Claims. (Cl. 15—231)

1
This invention relates to improvements in pad holder and pad means for use in the cleaning and conditioning of floors, walls and the like.

The present invention is in the nature of an improvement on the pad holder and pad means disclosed in my prior patent application Serial Number 594,645, filed May 19, 1945 (now abandoned).

The general object of my invention is to provide a mop type pad holding device which may be used by a person in a standing position to clean or condition a wall or floor by the use of the proper cleaning, waxing and polishing pads.

Another object is to provide a pad holder and pad means that may be efficiently used in applying cleaners to a surface to be cleaned without requiring the user to get these cleaners on the hands, thus making it possible to safely use cleaning solutions that will injure the hands if they come in contact therewith.

Another object of this invention is to provide a mop type pad holder to which various pads of the form commonly used to condition floors and walls may be very quickly and easily attached and detached thus making this device especially suitable for home use to keep floors and walls in good condition.

Another object is to provide a pad holder comprising a substantially flat platen having angle shaped grooves in its bottom side along its front and rear edge adapted to receive the edge portion of a pad that extends across said platen and having resilient pad gripping means adapted to be drawn against said pad and into said grooves to secure the pad to the platen.

Other objects of the invention will be apparent from the following description taken in connection with the accompanying drawings.

In the drawings—

Figure 1 is a plan view of a pad holding device constructed in accordance with this invention looking in the direction of broken line 1—1 of Fig. 2 and showing the pad gripping means in an open position, a portion of the handle being broken away.

Fig. 2 is a side elevation of the pad holding device shown in Fig. 1 showing the pad gripping members in an open position.

Fig. 3 is a side elevation similar to Fig. 2 showing a pad in an operative position and clamped by the pad gripping members.

Fig. 4 is a cross sectional view taken substantially on broken line 4—4 of Fig. 3 and on a larger scale than Fig. 3.

Fig. 5 is a view partly in plan and partly in sec-

2
tion taken substantially on broken line 5—5 of Fig. 3.

Fig. 6 is a view in cross section taken on broken line 6—6 of Fig. 5.

5 Like reference numerals designate like parts throughout the several views.

The pad holding means shown in Figs. 1 to 6 comprises a flat rectangular block or platen 10 having a handle 11 secured to the upper side thereof by any suitable means, such as a bracket 12. Preferably the handle 11 is about the same length as an ordinary broom or mop handle and is positioned at about the angle shown in the drawings to the plane of the platen for convenient application to the floor or wall.

The bottom surface of the platen 10 has an angularly shaped groove 13 extending along its front edge and another angularly shaped groove 14 extending along its rear edge to receive the marginal portions 15 of a pad 16. Pads of different type may be used depending on the work to be done. For instance the pad may be a steel wool pad or it may be a pad body with sandpaper drawn over it, or it may be a pad with wax folded into it or it may be a polishing pad or a mop pad. In all instances the pads will be provided with marginal portions corresponding to the portions 15 and with a main pad portion suitable for the work to be done.

30 The edges 15 of any pad 16 that is to be used are firmly gripped and securely held by two resilient pad clamping wires 17 and 18 that cooperate with the respective grooves 13 and 14. The pad clamping wires 17 and 18 extend across the bottom of the platen 10 and are thence bent at right angles and extend upwardly past the ends of the platen 10 through notches 19 in the ends of said platen and are thence converged, as best shown in Fig. 1, and have hook shaped bends 20 on their upper ends. The hook shaped members 20 engage within holes 21 in a slide member 22.

The slide member 22 is of inverted U shape in cross section, see Fig. 4. The bottom edges of the slide member 22 are bent outwardly and are slidably held and guided beneath the inwardly bent portions 23 of a track plate 24. The track plate 24 is secured to the handle 11, as by screws 25. A binding wire 26 extends substantially all of the way around the platen 10 and has end portions 27 that are driven into the platen to hold said wire in proper position. Preferably this binding wire 26 is countersunk into the edges and ends of the platen 10. This binding wire 26 extends across the notches 19 that the pad clamping wires 17 and 18 pass through and cooperates

with the notches 19 in forming guide and retaining means for the pad clamping wires 17 and 18.

The slide member 22 is connected by a U-shaped wire link 28 with a lever arm 29. The lever arm 29 is connected with a bracket 30 by a pivot member 31. The bracket 30 is secured to the handle 11 near the upper end of the guide member 23—24. The rear or upper end portion of the link 28 passes through a hole 32 in the lever arm 29 and the forward or lower ends 33 of the U-shaped link 28 are bent inwardly and shaped like hooks and are engaged within holes 34 in the slide 22. The pivot 31 in the bracket 30 is far enough away from the handle 11 so that the line of pull of the link 28 will cross from one side to the other of the axis of this pivot 31 in the operation of the lever 29. This line of pull on link 28 will be between the axis of the pivot 31 and the handle 11 when the lever 29 lies against the handle 11 and will be on the other side of the axis of the pivot 31 when the lever 29 is moved outwardly away from the handle 11. Thus the line of pull of the link 28 will pass the center of pivot 31 and a self locking link and lever structure will be provided.

The portions of the pad clamping wires 17 and 18 that operate in the slots 19 are substantially straight and substantially at right angles to the pad clamping portions of said wires and are joined to the convergent portions of these wires by bends 35. When tension is exerted on these wires it tends to straighten them at the location of the bends 35 and this contributes to the resiliency of the wires and makes them self adjusting to pads having marginal portions 15 of varying thickness. Preferably the pad engaging portions of the wires 17 and 18 are curved or bowed as shown in Fig. 2 to provide a firm grip on the edges 15 of the pad all of the way across the platen.

The two pad clamping members 17 and 18 are spread apart a greater distance at the location where they pass through the notches 19 in the platen 10 than they are at the location of the slide member 22, see Figs. 2 and 3. This provides a divergence of these pad clamping members which makes it easier to insert and remove pads than it would be if said wire pad clamping members did not so diverge. When these pad clamping members are moved from the position shown in Fig. 3 to the position shown in Fig. 2 they will be spread apart at the same time they are moved outwardly away from the platen 10. Thus they will drop any pad held thereby and will be wide enough apart to permit quick and easy application of another pad to the platen 10, after which the members 17 and 18 can easily be clamped against the pad so applied. The ease with which the pads are applied to and removed from this device renders it particularly desirable for ordinary home use.

The foregoing description and accompanying drawings clearly disclose a preferred embodiment of this invention but it will be understood that this disclosure is merely illustrative and that such changes in the device may be made as are within the scope and spirit of the following claims.

I claim:

1. In a pad holder, a relatively flat rectangularly shaped platen having angularly shaped grooves in its bottom side along its front and rear edge adapted to receive the edge portions of a pad that extends across said platen; pad gripping wires extending longitudinally of said platen

at the location of said grooves and extending upwardly past the ends of said platen and thence converging toward each other, the longitudinally extending pad gripping portions of said wires being bowed toward said grooves; and lever means connected with the converging portions of said pad gripping wires for drawing the bowed portions of said pad gripping wires into contact with the edge portions of a pad and pressing said edge portions of said pad into said grooves with a substantially uniform pressure from end to end of the pad.

2. In a pad holder, a relatively flat rectangularly shaped platen having a corner groove in its bottom side along its front edge and another corner groove in its bottom side along its rear edge, said grooves being adapted to receive the edge portions of a pad that extends across said platen; a handle secured to said platen mid way between the two ends of the platen and extending upwardly and rearwardly therefrom; two pad gripping wires extending longitudinally of said platen at the location of said grooves and extending upwardly past the ends of said platen and thence being bent and converging toward said handle; means on the ends of said platen for guiding said wires; and lever means on said handle connected with the converging portions of both of said pad gripping wires for drawing said wires into engagement with the edge portions of a pad to hold said pad, the bends in said wires providing sufficient resilience to render said wires self adjusting to pad edge portions of varying thickness.

3. In a pad holder a relatively flat platen having a corner groove in its bottom side along its front edge and another corner groove in its bottom side along its rear edge, said grooves being adapted to receive the edge portions of a pad that extends across said platen; a handle secured to said platen mid way between the two ends of the platen and extending upwardly and rearwardly therefrom pad gripping wires extending longitudinally of said platen at the location of said grooves and extending upwardly past the ends of said platen and thence being bent and converging toward said handle; a slide member connected with the convergent portions of said wires; means guiding said slide member for movement longitudinally of said handle; a lever fulcrumed on said handle above said slide member; and link means connecting said slide member and said lever, whereby angular movement of said lever will exert a pull on said pad gripping wires.

4. In a pad holder, a relatively flat platen having a corner groove in its bottom side along its front edge and another corner groove in its bottom side along its rear edge, said grooves being adapted to receive the edge portions of a pad that extends across said platen; notches in the ends of said platen in alignment with said grooves; pad gripping wires extending longitudinally of said platen at the location of said grooves and extending upwardly through said notches past the ends of said platen and converging toward each other above said platen; a binding wire extending around the marginal portion of said platen over said notches and cooperating with said notches to provide guide means for said pad gripping wires; and means for drawing said pad gripping wires into contact with the edge portion of a pad on said platen.

5. Pad holding means comprising a platen; two pad holding wires having pad engaging portions extending longitudinally across the bot-

tom face of said platen near the front and rear edge respectively of said platen and having other portions disposed substantially at right angles to said pad engaging portions and extending upwardly past the two ends of said platen; guide means in the ends of said platen for the upwardly extending portions of said wires; and operating means positioned above said platen and connected with said wires for moving the same, said guide means and said operating means supporting said two pad holding wires in divergent relation from top to bottom whereby the pad engaging portions of said wires will be moved divergently simultaneously with their movement away from said platen to thereby facilitate insertion and removal of pads. 15
